UNITED STATES PATENT OFFICE

104,599

DESIGN FOR A SWEAT SHIRT

Harry Charles, Norwich, N. Y., assignor to Norwich Knitting Company, Norwich, N. Y., a corporation of New York

Application April 6, 1937, Serial No. 68,582

Term of patent 7 years

To all whom it may concern:

Be it known that I, Harry Charles, a citizen of the United States and a resident of Norwich, in the county of Chenango and State of New York, have invented the new, original, and ornamental Design for a Sweat Shirt, of which the following is a specification, reference being had to the accompanying drawing, forming part thereof.

I claim:

The ornamental design for a sweat shirt as shown.

HARRY CHARLES.
